Specification for Design.

Patented Apr. 26, 1921.

Application filed April 9, 1920. Serial No. 372,677. Term of patent 14 years.

To all whom it may concern:

Be it known that I, LOUIS PERKINS BERRY, Jr., a citizen of the United States, residing at Memphis, in the county of Shelby and State of Tennessee, have invented a certain new, original, and ornamental Design for Sewage Apparatus, of which the following is a specification, reference being had therein to the accompanying drawing.

The figure in the drawing is a perspective view of the apparatus embodying my design.

I claim:

The ornamental design for sewage apparatus as shown.

In testimony whereof I hereunto affix my signature.

LOUIS PERKINS BERRY, JR.
